J. H. BURNFIELD

DIRIGIBLE HEADLIGHT

Filed Dec. 1, 1927

J.H.Burnfield

By Watson E. Coleman
Attorney

UNITED STATES PATENT OFFICE.

JAMES H. BURNFIELD, OF SOUTH AKRON, OHIO.

DIRIGIBLE HEADLIGHT.

Application filed December 1, 1927. Serial No. 237,033.

This invention relates to dirigible headlights and more particularly to a means for establishing the electrical connections of the illuminating elements of such lights.

5 A more specific object of the invention is the improvement of the conducting system illustrated in my prior patent, No. 1,649,661, granted November 15, 1927, for dirigible headlights, to enable the same to be more 10 readily applied to the headlight mounting structure and to provide a structure which is substantially dirt and water-proof and which may, at the same time, be readily removed for replacement or repair.

15 These and other objects I attain by the construction shown in the accompanying drawing, wherein for the purpose of illustration is shown a preferred embodiment of my invention and wherein:—

20 Figure 1 is a vertical sectional view showing contact mechanism for dirigible headlight apparatus constructed in accordance with my invention;

25 Figure 2 is a view with the cap removed, parts being broken away.

Referring now more particularly to the drawing, the numeral 10 generally designates a tubular casing having upper and lower bearing supports 11, in which are 30 mounted bearings 12 for a shaft 13. The shaft 13 has at its upper end an enlargement 14 seating upon the upper bearing 12 and above this the enlargement is provided with an extension, the upper end of which is 35 screw-threaded, as at 14^a. Seated upon the enlargement is a cap 15, the depending flange 16 of which extends in close proximity to the wall of the casing 10. This cap is maintained in position by a sleeve 17 and a nut 40 18. Between the nut and sleeve, the extension extends through a headlight casing 19, the lower end of which confronts the cap.

The upper bearing support 11 is recessed in its upper face for the reception of an 45 arcuate contact strip 20, which is insulated from the casing. In the present instance, this upper bearing support is disclosed as having embedded therein an insulating strip 21, in which the contact is seated, although 50 it will, of course, be understood that if desired, the entire support may be formed of

insulating material. At one side, the upper bearing support is notched, as indicated at 22, and the contact 20 has a depending flange 23 extending into this notch and opposing 55 the side wall of the casing 10 in spaced relation thereto. This flange is likewise held in spaced relation to the walls of the notch where the upper bearing support is of conducting material, as illustrated in the present 60 instance. To this end, the insulating insert, which is at the notch 22, is provided with a shallow notch 24, the side edges of which closely fit against the side edges of the flange and the base of which is spaced outwardly 65 from the base of the notch 22.

The wall of the casing 10 in opposition to the flange 23 is relatively thickened and provided with a radial bore 25 within which is arranged an insulating plug 26, the inner end of this plug having a socket 27 within which is arranged a spring 28 bearing upon a brush 29 which contacts the flange 23. This brush has electrically connected therewith a lead wire 30, which extends through 75 a reduced continuation 31 of the bore to the outer end of the insulating plug and through an opening formed in a cap 32, which retains the plug in position within the bore 25.

The cap 15 in opposition to the contact 20 is formed with an opening 33 through which is directed an insulating plug 34 having a socket 35 in its inner end, within which is arranged a spring 36 bearing upon a brush 37 engaging the contact. This plug is 80 formed with a flange 38 engaging the upper face of the cap and fitting thereagainst and above the flange has a reduced extension 39, which is of greater length than the collar 17. The plug and its extension have an axial 85 passage 40 for a lead wire which is electrically connected to the brush 37. Any suitable means may be provided for securing the plug in position upon the cap. In the present instance, the lower end of the plug and 90 the bore 33 of the cap are shown as having 95 coacting screw threads.

It will be obvious that with a device of this character, an excellent electrical connection between the lead wires 30 and 40 100 may be had in all positions of the cap which rotates with the shaft 13 to change the posi-

tion of the headlight casing. In applying the headlight casing, openings are formed therein, for the passage of the extensions 14^a of the shaft and 39 of the plug. These extensions thus cooperate with the casing to prevent rotation thereof with relation to the cap and the nut 18 will, of course, prevent vertical displacement of the casing. Since the upper end of the extension 40 projects into the headlight casing, no water may enter at the upper end thereof to cause short-circuiting and entrance of the water about the plug 34 is prevented by the flange 38 and the screw-threaded connection of the plug. Either of the contacts 29 or 37 may be readily removed for inspection, repair or replacement.

It will be obvious that this structure may be very readily and cheaply produced and will be durable and efficient in service. Since the construction hereinbefore set forth is capable of a certain range of change and modification without materially departing from the spirit of the invention, I do not limit myself to such specific structure except as hereinafter claimed.

I claim:-

1. In a headlight mounting, a tubular housing, upper and lower supports within and held against rotation with relation to the housing, a headlight supporting shaft rotatable in said supports, a cap for the casing carried by and held against rotation with relation to the shaft, an arcuate contact carried by the upper support and insulated from the casing and having a flange opposing the casing wall, a brush support directed through the casing wall and having a brush engaging said flange and a second brush support directed through the upper wall of the cap and having a brush engaging the arcuate contact.
2. In a headlight mounting, a tubular housing, upper and lower supports within and held against rotation with relation to the housing, a headlight supporting shaft rotatable in said supports, a cap for the casing carried by and held against rotation with relation to the shaft, an arcuate contact carried by the upper support and insulated from the casing and having a flange opposing the casing wall, a brush support directed through the casing wall and having a brush engaging said flange, a second brush support directed through the upper wall of the cap and having a brush engaging the arcuate contact.
3. In a headlight mounting, a tubular housing, upper and lower supports within and held against rotation with relation to the housing, a headlight supporting shaft rotatable in said supports, a cap for the casing carried by and held against rotation with relation to the shaft, an arcuate contact carried by the upper support and insulated from the casing and having a flange opposing the casing wall, the upper end of the second brush support extending through an opening formed in the headlight casing to the interior thereof.
4. In a headlight mounting, a tubular housing, upper and lower supports within and held against rotation with relation to the housing, a headlight supporting shaft rotatable in said supports, a cap for the casing carried by and held against rotation with relation to the shaft, an arcuate contact carried by the upper support and insulated from the casing and having a flange opposing the casing wall, the casing wall in opposition to said flange having an opening, a brush support mounted in said opening and having a spring-pressed brush engaging said flange, a cover plate for the opening retaining the brush support in position therein and a second brush support directed through the upper wall of the cap and having a brush engaging the arcuate wall of the contact.
5. In a headlight mounting, a tubular housing, upper and lower supports within and held against rotation with relation to the housing, a headlight supporting shaft rotatable in said supports, a cap for the casing carried by and held against rotation with relation to the shaft, an arcuate contact carried by the upper support and insulated from the casing and having a flange opposing the casing wall, a brush support directed through the casing wall and having a brush engaging said flange, the cap having an opening in opposition to the arcuate contact, a brush support directed through said opening and having sealing engagement with the cap and a spring-pressed brush carried by the brush holder and engaging the arcuate contact.
6. In a headlight mounting, a tubular housing, upper and lower supports within and held against rotation with relation to the housing, a headlight supporting shaft rotatable in said supports, a cap for the casing carried by and held against rotation with relation to the shaft, an arcuate contact carried by the upper support and insulated from the casing and having a flange opposing the casing wall, the casing wall in opposition to said flange having an opening, a

rotatable in said supports, a cap for the casing carried by and held against rotation with relation to the shaft, an arcuate contact carried by the upper support and insulated from the casing and having a flange opposing the casing wall, a brush support directed through the casing wall and having a brush engaging said flange, a second brush support directed through the upper wall of the cap and having a brush engaging the arcuate contact, a headlight casing secured to the upper end of the shaft, the upper end of the second brush support extending through an opening formed in the headlight casing to the interior thereof, and means sealing said second brush support to the cap at the point of its passage therethrough.

7. In a headlight mounting, a tubular housing, upper and lower supports within and held against rotation with relation to the housing, a headlight supporting shaft rotatable in said supports, a cap for the casing carried by and held against rotation with relation to the shaft, an arcuate contact carried by the upper support and insulated from the casing and having a flange opposing the casing wall, a casing wall in opposition to said flange having an opening, a brush support mounted in said opening and having a spring-pressed brush engaging said flange, a cover plate for the opening retaining the brush support in position therein and a second brush support directed through the upper wall of the cap and having a brush engaging the arcuate wall of the contact.

8. In a headlight mounting, a tubular housing, upper and lower supports within and held against rotation with relation to the housing, a headlight supporting shaft rotatable in said supports, a cap for the casing carried by and held against rotation with relation to the shaft, an arcuate contact carried by the upper support and insulated from the casing and having a flange opposing the casing wall, a brush support directed through the casing wall and having a brush engaging said flange, the cap having an opening in opposition to the arcuate contact, a brush support directed through said opening and having sealing engagement with the cap and a spring-pressed brush carried by the brush holder and engaging the arcuate contact.

9. In a headlight mounting, a tubular housing, upper and lower supports within and held against rotation with relation to the housing, a headlight supporting shaft rotatable in said supports, a cap for the casing carried by and held against rotation with relation to the shaft, an arcuate contact carried by the upper support and insulated from the casing and having a flange opposing the casing wall, the casing wall in opposition to said flange having an opening, a

brush support mounted in said opening and having a spring-pressed brush engaging said flange, a cover plate for the opening retaining the brush support in position therein, 5 the cap having an opening in opposition to the arcuate contact, a brush support directed through said opening and having sealing en-

gagement with the cap and a spring-pressed brush carried by the brush holder and engaging the arcuate contact. 10

In testimony whereof I hereunto affix my signature.

JAMES H. BURNFIEL.
